UNITED STATES PATENT OFFICE.

EDWARD WESLEY BURGESS, OF MILWAUKEE, WISCONSIN, ASSIGNOR TO A. O. SMITH CORPORATION, OF MILWAUKEE, WISCONSIN, A CORPORATION OF NEW YORK.

STORAGE-BUILDING.

1,344,617.

Specification of Letters Patent. Patented June 29, 1920.

Application filed February 11, 1919. Serial No. 276,329.

To all whom it may concern:

Be it known that I, EDWARD WESLEY BURGESS, a citizen of the United States, residing in the city of Milwaukee, county of Milwaukee, and State of Wisconsin, have invented a new and useful Improvement in Storage-Buildings, and do declare that the following is a full, clear, and exact description thereof, such as will enable persons skilled in the art to which the invention pertains to make and use the same, reference being had to the drawings hereto attached for disclosure as to certain details of the construction.

15 My invention relates to a storage building, which, while especially designed for a specific purpose, is capable of use for many general storage purposes.

The storage building hereinafter disclosed 20 has been designed for construction as an adjunct to a plant conducting very large operations in connection with the manufacture of automobile frames, and in which the daily production of the plant has reached 25 such proportions that the problems attending the expeditious handling and storing of such daily output have assumed a very serious aspect, and have rendered imperative the demand for a new type of construction 30 of storage buildings, to overcome the inadequacies and consequent inconveniences of the storage buildings now used for like purposes.

In storing large quantities of articles, 35 such as automobile frames, which although very bulky are yet light in weight in comparison to their bulk, the demands for storage space increase very rapidly. Such articles as automobile frames cannot be stacked 40 in piles containing more than a limited number of frames, for the reason that the weight of the several frames in the pile will distort the frames at the bottom thereof. In addition, the number of such frames which may 45 be so stacked or piled is limited to such number as will constitute a stack or pile which may be handled conveniently as a unit, it being the practice for reasons of economy as well as expedition, to so handle 50 such stacks or piles as units in storing automobile frames. Hence, if ground floor storage only be used, the cost of a storage building of ample dimensions will require

an outlay much out of proportion to the results secured, to say nothing of the needless 55 waste of time required to transport the frames over the long reaches of such a building. The practice of storing in a smaller building having several floors, is expensive and inefficient, and open to the objection that too much time is required to transfer the stacks or piles of frames from the hoist to the floor trucks and distribute them over the several floors of the building, and to withdraw them from storage. 65

I have invented a storage building and so constructed it that the objections to the former methods of storing are completely eliminated, and I do this at a minimum structural cost for the building. My improved storage building will cover only the usual or a comparatively small area of ground, but in external appearance will resemble a building having a height of several stories. However, the building will be 70 clear from the ground floor to the roof, except for the skeleton frame work used in my system of storage, and I have thus released for storage purposes practically the whole of the cubical area of that part of the 75 interior of the building set apart for the storage of frames and other automobile parts.

The building is of good factory construction, with a trussed roof. Rising from the 80 floor and extending to the roof at suitable places in the interior of the building, are several parallel rows of columns which at certain levels are provided with brackets for supporting a series of longitudinal 85 stringers, such brackets and stringers extending a limited distance into the aisles formed by the said parallel rows of columns. A wide space between the stringers supported by one row of columns and the 90 stringers of the next row is preserved, and into and through this space the carrier or cradle for conveying the material to be stored may be moved, both vertically and horizontally. A mono-rail hoist system, 95 supported at the top of the columns, is arranged centrally over each aisle, and on the track of this system travels an electric hoist, to which is attached the cradle for the material to be stored. The material to be 100 stored, in the present instance consisting of

65

105

a stack or pile of automobile frames, all of the frames constituting such stack or pile being of uniform construction, will be carried in the cradle to the desired position for storage, and deposited crosswise of the aisle, upon the stringers supported by the vertical columns forming the aisle.

In the manufacturing plant in connection with which the storage building herein described is being erected as an adjunct, the organization is such that automobile frames are produced by mechanical devices operating upon a schedule providing for the completion of a given number of frames per minute. Upon completion, the frames are stacked or piled at a point within the reach of the mono-rail system carrier cradle, which latter immediately transports the stack or pile of frames to the selected place of storage, and returns for another load.

The provision of superposed storage levels, created by the stringers extending slightly into the storage aisles, necessitates the use of a carrier cradle of peculiar construction. The cradle which I have devised for this purpose is in the form of a skeleton, and is open at one side and at both ends. These structural features enable me to move the cradle laterally to receive the stack of frames, and to transfer the stack to its place of storage by passing the cradle into the storage level and depositing the load by resting the projecting ends of the stack of frames on the stringers.

The storage building is provided with a receiving station and with a shipping station, to each of which a railway will be run, so that unloading raw materials as well as loading the finished work for shipment may be performed within the inclosure of the storage building.

I propose to reserve the floor of the building for the storage of raw materials, such as the steel sheets or plates used in the manufacture of automobile frames, and at a suitable distance overhead have arranged a low-level mono-rail hoist system for handling such raw material. The clear space above that reserved for the storage of raw materials, and its co-operating mono-rail hoist system, is divided by the brackets and stringers, before referred to, into a plurality of sub-spaces suitably proportioned to the height of the stacks or piles of automobile frames which can be conveniently stored therein.

In the drawings accompanying this specification,

Figure 1 is a sectional plan view, showing generally the outlines of the storage building, together with the arrangement of the columns supporting the storage means, and the course of the mono-rail hoist systems employed in the building.

Fig. 2 is a sectional view in elevation,

broken out at places, looking from the bottom, Fig. 1.

Fig. 3 is a sectional view in elevation, likewise broken out, looking from the left, Fig. 1.

Fig. 4 is a view, somewhat enlarged, showing in end elevation, the formation of a channel bar, the like of which constitute the stringers hereinafter described as being employed in the construction of the storage building constituting the present invention.

Referring to the drawings, in which Figs. 2 and 3 are sectional views of a storage building, of suitable construction, a series of parallel rows of vertical columns A, A', 75 rise from the floor to the roof. Set in each of the walls of the building is a row of other vertical columns, A'', A''', the latter being aligned with the rows of columns in the open interior of the building. These columns together with the walls of the building, rest upon suitable footings, as is customary in building constructions, and the roof structure is supported at the top of the said walls and columns.

At the right hand end of the building, as viewed in Fig. 2, a portion of the floor is left clear and set apart for use as a receiving station, and a similar space at the left hand end of the building is left clear and set apart for use as a shipping station. A railway is run to each of these stations, so that railway cars bearing raw materials may be discharged within the building at the receiving station, and likewise, 100 cars may be loaded for shipment at the shipping station.

A gauntlet crane C is located over the railway at the receiving station, and a transfer bridge D is likewise located at the 105 shipping station. The uses of these mechanisms are well known, and forming no part of the present invention, their construction will not be further described.

At intervals, the vertical columns are tied by longitudinal beams A'', and cross beams A'', at a level some distance above the floor, and the space between the said beams and the floor, and between the railway stations, is reserved for the storage of raw material, 110 such as the steel sheets or plates, from which the automobile frames are made.

Suspended from the cross beams A'', over the steel storage space, is the track E, of a low-level mono-rail system, the course of which is shown in Fig. 1, and which extends centrally of the longitudinal aisles formed by the rows of vertical columns. This track E is continued over the receiving station, and at the end of its longitudinal runs, 120 merges into a line parallel with and directly over the railway at such station. Suitable switches are provided at all junctions, for directing the traveling electric hoist E', upon whichever track may be desired. As 130

indicated at *x* in the lower right of Fig. 1, the track may be extended beyond the building and the hoist may be used to carry materials into the building.

5 The gauntlet crane *C* is employed, among other purposes, for unloading the sheet metal plates from the railway car. These plates are deposited on the station platform, where they will be evened up. The hoist *E'*, of the 10 low-level mono-rail system, is equipped with a series of electro-magnets *E*², which when energized and lowered into contact, are adapted to pick up the stacks of sheet metal plates previously unloaded from the car by 15 the gauntlet crane, and evened up. The hoist will then carry such plates into the selected aisle for storage at a designated place, upon reaching which the magnets will be de-energized, and the stack of metal plates allowed to rest in their evened-up condition. 20 When not in use, the gauntlet crane will be moved along its tracks until it rests at one side of the building, and out of position to interfere with the movements of the hoist *E'*. 25 The transfer bridge *D*, like the gauntlet crane, will be run to the side of the building when not in use, or when it is desired to clear the shipping station for the movement of the mono-rail hoist, hereinafter described 30 as operating at the shipping station.

It has been found desirable to leave an open bay *F*, through the longitudinal center of the building, between the rows of columns *A'*, *A'*, for various purposes.

35 At suitably spaced points above the level of beams *A*⁴ and *A*⁵, the vertical columns *A*, are provided with double brackets *A*⁶, which are attached at their mid-lengths to the columns *A*. These brackets may be formed of 40 sections of I-beams or of channel bars. At their free ends, the brackets *A*⁶, support stringers *A*⁷, formed of channel bars, which extend longitudinally of the building, through the aisles formed by the vertical 45 columns. The columns *A'*, which border on the bay *F*, and the columns *A*², set in the side walls of the building, are provided with single brackets *A*¹⁰ and *A*²⁰, respectively, which extend into the adjacent aisles. 50 The single brackets thus supported, carry stringers *A*⁷ complementary to the stringers across the respective aisles. The columns *A* and *A'*, are braced by diagonal tie rods *A*⁹.

A track *G*, of a high-level mono-rail system hoist is supported at the top of the vertical columns *A*, *A'*, *A*² and *A*⁸, and over this track moves an electric hoist *G'*. The course of the track is indicated diagrammatically in Fig. 1, from which, as well as 55 from Fig. 3, it will be seen that the track is arranged centrally over the aisles formed for the storage of stacks or piles of automobile frames. A spur *y*, of the track extends into the bay *F*, as indicated in Fig. 1. 60 As in the case of the low-level track *E*, the

track *G*, will be provided with switches at all junctions, so that the hoist may be directed into any desired storage aisle.

One use to which I propose to put the bay *F*, is to install therein an apparatus for 70 painting the automobile frames. Upon completion of the painting operation, the frames will be automatically delivered at a suitable level under the spur *y*, of the track *G*, and in position to be taken by the hoist *G'*, to 75 the desired place for storage.

The hoist *G'*, is provided with a skeleton cradle *G*², which is open at one side and at both ends, as indicated in Fig. 2, for the reception of a stack of automobile frames *G*³. 80 The stack of automobile frames to be stored will be pillow'd on bars or blocks, so as to allow a clearance sufficient for passing the lower fingers of the cradle under such stock, and thus the stack is received in the cradle 85 by lateral movement of the hoist, under the direction of the operator.

The hoist will now move the cradle with its load to the desired storage aisle, and then into the aisle, and to the space selected 90 for storage, where the hoist will deposit the load upon the stringers *A*⁷, the stack of automobile frames thus bridging the distance between the stringers in the aisle at that particular level. The outer ends of 95 the lower frame in the stack, projecting beyond the sides of the cradle, rest upon the stringers, and thus the stack is stored. In passing along the aisle to the place selected for storage, the stack of frames will move 100 clear of the stringers above as well as those below, and upon depositing the load by letting out the cables, the cradle will be free from any contact with the stack, and can then retire for another load.

105 The channel bars comprising the stringers *A*⁷, are provided with a frame supporting surface *a*⁷ upon which the ends of the lower frame of the stack of automobile frames will rest, when the stack is deposited in its storage position. The said frame supporting surface *a*⁷ is reinforced by the vertical web *a*⁷⁰, whereby rigidity of the means upon which the stored articles rest is achieved, and deflection thereof under the weight of the 110 stacks of frames is prevented.

115 At the left of Fig. 3, I have indicated the progress of the storing operations. The start is made by filling the remotest space in any given level, then storing until the level 120 has been filled, whereupon the next level above will be filled, and so on. After the aisle has been stored, the next aisle will be taken. However, as a matter of convenience in removing the frames from storage for 125 shipment, I have found it advisable to store only frames of a given type and uniform size in one aisle, using different aisles for frames of different types and sizes.

When the frames are to be shipped, a hoist 130

4
G', operating over the shipping station, will take the stacks of frames from the storage aisles, and deposit them upon the floor of the station, in position for convenient loading in 5 railway cars. The hoist used in withdrawing the frames from storage may be the hoist used for placing the frames in storage; or, it may be a different hoist but of like construction, both operating over the track G.

10 Great quantities of light parts may be stored in my building, by using bins of suitable dimensions for holding such small parts. These bins are handled and conveyed by the hoist and its cradle, just as 15 are the stacks or piles of automobile frames, I have indicated one of such bins at z, in storage position at the right of Fig. 3.

From what has hereinbefore been disclosed, it will be obvious that my new and 20 improved storage building has as its great advantage the complete utilization for storage purposes of what is practically the solid cubical area of the space set apart for storage. It will be obvious also, that this result 25 is secured by a system of superposed storage, such as would require a building of similar dimensions to be provided with several floors for the reception of the same amount of material.

30 The results flowing from the use of my invention are that in a building of given length, width and height, I am enabled to dispense with the several floors, and yet 35 pack the storage space solidly from bottom to top, with but a slight allowance of space for occupation by the skeleton frame work used in my storage system.

The stack of frames will be received by 40 the pendent cradle of the hoist in a state of equilibrium, so that there will be no uneven movements of the load during transportation to storage. This cradle, which is of the peculiar form described, is a necessity in 45 the operation of my invention. It will receive the load by relatively lateral movement through the open front thereof, and will discharge the load when the latter has been placed in storage position, simply by retiring after the cradle has been freed from 50 engagement with such load. The provision of the open ends from which the frames project, enables me to bring about the disengagement and deposit of the load by resting the free ends of the latter upon the offset 55 stringers supported by the columns. The rows of columns are set apart such distances as will permit the unobstructed passage of stacks of frames into the open ends of the storage levels, without contact with 60 the columns. In the building embodying the invention, the rows of columns are set eighteen feet on centers, with a clearance of nine feet between the stringers in each aisle, at the storage level. But in erecting a storage building in accordance with my inven- 65

tion, the proportions may be such as to meet general requirements or the requirements of any particular case.

The low level hoist and the storage space, which latter in the construction hereinbefore described, has been designed for the storage of heavy materials, may be omitted and the whole of the storage area of the building be converted into storage levels of the kind described, without departing from the spirit of my invention. Broadly, my invention resides in a construction in which storage aisles are formed by rows of columns which support stringers offset from the columns to divide the aisles into storage levels, irrespective of any auxiliary storage provisions.

70 In an application filed February 7, 1920, Serial #356,943, which is a division of the present application, I have claimed the storage building and the hoist used in connection therewith, it being my intention to limit the claims of the present case to the storage building *per se*.

75 Having thus described my invention, what I desire to secure by Letters Patent is:—

80 1. A storage building, the interior of which is provided with rows of columns which form storage aisles open from bottom to top, and stringers supported by the columns of each row, and offset therefrom to 85 form storage levels.

85 2. A storage building, the interior of which is provided with rows of columns which form storage aisles open from bottom to top, and a plurality of longitudinal stringers offset from and supported by the columns, to subdivide the aisle into a series 90 of superposed storage levels which are open at their ends.

95 3. A storage building having rows of vertical columns therein, and substantially parallel stringers supported at the respective sides of each row of columns and offset therefrom, to form spaced sets of stringers supported between adjacent rows of columns and sufficiently distant from the columns to allow articles to be stored to pass between adjacent rows of the columns, with 100 their ends above the stringers.

105 4. A storage building, the interior of which is provided with rows of columns which form storage aisles, open from bottom to top, cross brackets attached to the columns at spaced intervals, and stringers supported by the brackets to form storage 110 levels.

115 5. A storage building comprising rows of columns which divide the storage space into vertical storage aisles, and means carried by the columns for sub-dividing the said aisles 120 into storage levels and supporting the articles to be stored at points offset laterally from the rows of columns.

125 6. A storage building comprising rows of columns which divide the storage space into 130

- vertical storage aisles, and longitudinal stringers supported by and extending laterally of the columns and sub-dividing the aisles into storage levels, the width of the 5 storage aisles exceeding the distance between the longitudinal stringers, so that the articles to be stored may be placed in the storage levels and supported therein at points offset from the rows of columns.
- 10 7. A storage building comprising rows of vertical columns which divide the storage space into storage aisles which are open from bottom to top, and longitudinal stringers supported by the columns for sub-dividing 15 the aisles into open-end storage levels, into which the articles to be stored may be deposited with their ends supported upon the stringers at points offset laterally from the rows of columns.
- 20 8. A storage building for the storage of stacks of automobile frames, such building comprising rows of vertical columns which form the side walls of the storage aisle, and means supported by the said side walls sub-25 dividing the aisle into storage levels which are open at their ends and for supporting the stacks of automobile frames upon lines parallel to but removed from the side walls of the storage aisle.
- 30 9. A building for the storage of stacks of

automobile frames, provided with rows of vertical columns, and longitudinal stringers supported by the columns to sub-divide the aisle formed by the rows of columns into open-end storage levels, into which levels the 35 stacks of frames may be freely passed and stored by resting the ends of the lower frame of each stack upon the stringers at points offset laterally from the adjacent rows of columns.

10. A storage structure for stacks of automobile frames, comprising rows of columns dividing the storage space into aisles, and longitudinal stringers supported by the said columns and sub-dividing the aisles into independent frame supporting storage sections, such stringers providing supporting surfaces upon which the stacks of frames may be deposited when moved along the aisles, and a reinforcement for such frame 40 supporting surfaces at points offset from the columns.

In testimony whereof, I have signed my name, in the presence of two witnesses, this 4th day of February, 1919.

E. W. BURGESS.

Witnesses:

W. F. WOOLARD,
C. FUCHS.
